UNITED STATES PATENT OFFICE.

CHARLES NELSON, OF NEW YORK, N. Y., ASSIGNOR TO S. STERNAU & CO., OF BROOKLYN,
NEW YORK, A COPARTNERSHIP.

DESIGN FOR A CRUMB-TRAY.

42,974.

Specification for Design.

Patented Sept. 3, 1912.

Application filed May 28, 1909. Serial No. 499,060. Term of patent 14 years.

To all whom it may concern:

Be it known that I, CHARLES NELSON, a subject of the King of Sweden, residing in the borough of Brooklyn, county of Kings, city and State of New York, have invented a new, original, and ornamental Design for a Crumb-Tray, of which the following is a specification, reference being had to the accompanying drawing, forming a part hereof.

The figure shows a perspective view of a crumb tray of my new design.

The design comprises a trapezoidal body having walls on three sides. These walls

slope outward away from the bottom of the body. On the upper edge is an overhanging ornamental band, the ornamentation being composed of alternate hemispherical and lateral straight grooves.

I claim:

The ornamental design for crumb tray, as shown and described.

CHARLES NELSON.
